UNITED STATES PATENT OFFICE.

NELSON S. WELK, OF ATHENS, OHIO, ASSIGNOR TO THE MCBEE BINDER CO., OF ATHENS, OHIO, A CORPORATION OF OHIO.

FILING TRAY.

Application filed February 25, 1926. Serial No. 90,476.

This invention relates to filing trays for cards and like matter, and has particular reference to means for retaining such cards in proper filed position.

5 It is an object of the present invention to provide an adjustable clamping plate, to be used in conjunction with a follower plate, such as that disclosed in my copending application, Serial Number 90,475, filed Feb. 10 25, 1926.

An object of the invention is the provision of a support for the clamping plate, whereby such plate is mounted to swing in a vertical plane.

15 A further object of the invention is the provision of mechanism for forcing said plate into clamping position, and retaining the same against accidental movement.

Another object is the provision of such 20 a structure of extremely simple construction, which is strong, durable and highly convenient in use.

Referring to the drawings:

Fig. 1 is a perspective view of a filing 25 tray embodying the invention,

Fig. 2 is a central, vertical, longitudinal section therethrough, and,

Fig. 3 is a perspective view of the clamping 30 plate and associated support removed from the tray.

Referring specifically to the drawings, the 35 numeral 10 designates the front wall of the tray, 11 the side wall and 12 the rear wall. The walls, 10, 11 and 12, are formed from a single sheet of suitably stiff sheet metal, bent upon itself at its upper edges, as indicated at 13, to provide a reinforced and smooth contacting surface. The walls are further reinforced by a substantially rigid 40 band 14, extending therearound, adjacent the upper edges, and projecting slightly beyond the front and rear walls 10 and 12. A bottom 15 is suitably, rigidly attached to the side and end walls 10, 11 and 12. The opposite side of the tray is formed open and is normally closed by a swinging door, designated as a whole by the numeral 16. The structure of the door 16 has been fully disclosed in my application above identified.

45 The ends 10 and 12, adjacent such opening, are further reinforced by vertical corner posts 17, welded or otherwise attached thereto. The front end 10 is provided with a handle 18 and an open card-pocket 19.

55 It is desirable that means be provided to

prevent distortion of the tray due to the door opening, and to overcome this objection, a strip 20 is welded or otherwise attached to the outer surface of the door, in alignment with the band 14, and extending beyond the ends of the door to form in effect a continuation of the band 14. The projecting ends of the strip 20 are provided with openings for the reception of pins 21, carried by the corner posts 17. It will thus be seen that when the door is in the closed position, the pins will engage the openings of the strip, consequently, any stress upon the ends of the tray will be supported by the strip 20.

It will be observed from the description 70 so far given that an exceptionally strong and convenient file tray has been provided. The drop side provides a means of ready access to the cards in the file and enables the operator to slide a card outwardly for further reference. The engagement of the strip 20 with the pins 21 will avoid any distortion of the tray when in use, due to the pressure exerted therein by the clamping plate, to be described.

The numeral 22 designates a substantially U-shaped track, extending longitudinally of the tray for its entire length, and bolted as shown or otherwise rigidly attached to the bottom thereof. This track is provided with 85 inturned flanges 23, to be engaged by the carriage 24 of a follower 25. The follower and associated parts have been described and claimed in detail in my co-pending application, Serial Number 90,477, filed on Feb. 25, 1926.

In order to provide a means of retaining the filed cards in compact and upright position, a compression or clamping plate has 95 been provided in the forward end of the tray. This plate is designated by the numeral 26, and is adapted to swing from a vertical or clamping position, forwardly to a position for relieving pressure on the cards. The plate 26 is hingedly supported as at 27, to the horizontal flange 28 of a substantially L-shaped supporting member 29. The member 29 extends transversely of the tray, and has its vertical wall 30 bolted or otherwise rigidly attached to the front wall of the tray, as shown. The material of the member 29 is bent inwardly at its top and upon itself, for forming a horizontal flange 31.

The numeral 32 designates an operating 110

lever for controlling the pressure of the plate 26. This lever is pivotally mounted as at 33, adjacent the lower end of the plate, and adapted for swinging movement across the 5 face of such plate. A combined wear strip and limiting means 34 is secured to the plate 26, and this strip has inturned ends 35 for limiting the swinging movement of the lever 32 in either direction. The lever 32 is provided with an L-shaped pivot member 36, carrying a pivot pin 37. A corresponding pivot pin 38 is carried by the flange 31, and these pins 37 and 38 receive a rigid link 39, the openings 40 of which are sufficiently 15 large to enable such link to partake of slight vertical movement, while swinging in a horizontal plane, due to the swinging of the lever 32 about its pivot. It will thus be seen that movement of the lever in the direction 23 of the arrow, (Fig. 3) will result in the plate being moved forwardly or to the release position, as shown in dotted lines, (Fig. 2). Movement of the lever in the opposite direction will result in the plate being moved 25 to the clamping position, and when in such position, the link 39 will have moved to a past center position, consequently, the plate 26 will be retained in clamping position, against accidental release by the pressure of 30 the cards.

The operation of the device is as follows:

Assuming that the tray contains filed matter such as cards, and that the parts are in the position illustrated in Fig. 1. It is now desired to inspect the cards, and to make this possible, the lever 32 is swung over to the left, thereby releasing the clamping plate 26. The follower plate 25 is then released and moved rearwardly. It is now 35 possible to inspect the cards, as all pressure has been relieved therefrom.

It will be observed from the foregoing that an extremely simple and efficient means has been provided for compressing or clamping the filed matter in proper position within the tray. The support for the clamping plate is rigidly carried by the front wall of the tray, and any unusual pressure upon the clamping plate will be distributed throughout the tray itself. The releasing or operating means for the tray is exceptionally simple and requires but a single shifting movement of the lever to move the plate in the required direction.

It is to be understood that the invention is not limited to the precise construction set forth but that it includes within its purview whatever changes fairly come within either the terms or the spirit of the appended claims.

Having thus described my invention, what I claim and desire to secure by Letters Patent of the United States, is:

1. A tray of the character described, comprising a rectangular sheet-metal body por-

tion, formed open at its top, a follower and a clamping plate mounted within said tray, the means for mounting said clamping plate comprising a support and means for hinging said clamping plate to said support, said support adapted to be bolted to the front wall of said body portion, means for forcing said plate into clamping position, and for retaining it in clamped position after adjustment and against accidental movement.

2. A filing tray of the character described, comprising a rectangular sheet-metal body portion, open at its top, a follower and a clamping plate mounted therein, the mounting means for said clamping plate comprising a support, means for hinging said clamping plate to said support for vertical swinging movement toward and from said follower, an operating lever, and means associated with said operating lever, and said support, for moving said clamping plate into, and retaining it in, clamped position.

3. A filing tray of the character described, comprising a rectangular body portion, formed open at its top, a clamping plate mounted therein, the means for mounting said clamping plate comprising a support and means for hinging said clamping plate to said support, an operating lever pivoted upon said clamping plate, means for limiting the swinging movement of said operating lever, a link connecting said operating lever and said support, said lever and said link, when in one position, adapted to lock said clamping plate in clamping position against accidental movement, and when moved to the opposite position, adapted to move said plate to the release position.

4. A filing tray of the character described, comprising a rectangular body portion, open at its top, a clamping plate therein, a support for said clamping plate, hinge elements connecting said plate with said support, means for rigidly securing said support within said tray, an operating lever pivoted to said clamping plate, stop means for limiting the movement of the operating lever in either direction, pivot elements carried by the support and the operating lever, a link engaging said pivot elements, the operating lever adapted, when moved to one position to move the link to a past-center position for retaining the plate in clamped position, and when moved to the opposite position, to release said plate by moving the same forwardly.

5. A filing tray of the character described, comprising a rectangular sheet-metal body portion, open at its top, a clamping plate mounted therein, for vertical swinging movement, the mounting means comprising a support formed of substantially L-shape, and provided with an overturned flange at its upper edge, said support adapted to be

- clamped to the forward wall of the body portion, an operating lever pivoted to said clamping plate for lateral swinging movement, pivot elements carried by said operating lever and the overturned flange of the support, a link engaging said pivot elements, said lever, when moved to one position, adapted to move said link to a past-center position for locking the plate in clamping position against accidental movement, said lever, when moved to the opposite position, adapted to retract the plate to the released position, and means for limiting the swinging movement of the lever.
- 10 6. A filing tray of the character described, comprising a rectangular body portion, open

at its top, a clamping plate therein, a support for said clamping plate, hinge elements connecting said clamping plate with said support, said support formed of substantially an L-shape, and with a horizontal wall and a vertical wall, said vertical wall bent inwardly at its upper edge and upon itself, forming a reinforcing flange, said vertical wall adapted to be bolted to the front wall 25 of the body portion, an operating lever for said plate, link means connecting said operating lever with said reinforced flange, whereby said plate may be moved to the clamping position, and means for limiting 30 the swinging movement of said lever.

NELSON S. WELK.
